Atty.

UNITED STATES PATENT OFFICE.

MERRITT SCOTT CONNER, OF ADELPHI, SALFORD, ENGLAND.

TELEPHONE RECEIVER.

1,404,584.

Specification of Letters Patent. Patented Jan. 24, 1922.

Application filed July 31, 1918. Serial No. 247,525.

To all whom it may concern:

Be it known that I, MERRITT SCOTT CONNER, a citizen of the United States of America, and resident of Peel Works, Adelphi, 5 Salford, in the county of Lancashire, England, have invented certain new and useful Improvements in Telephone Receivers, (for which I have filed application in Great Britain under date of July 2, 1918, filing No. 10 13167, accepted under No. 116201,) of which the following is a specification, such as will enable others skilled in the art to which it appertains to make and use the same.

This invention relates to improvements in 15 telephone receivers.

The object of the invention is to enhance the clearness and efficiency of sound reproduction.

The invention consists in providing a 20 shunt path in such relation to the pole pieces or polar extensions that magnetic flux induced in the pole pieces by sound currents in the coils will in large measure flow by way of the said shunt path and thus lower 25 the total reluctance and hysteresis losses of the apparatus and thereby improve the reproduction of speech.

The said shunt path is provided in any 30 suitable manner below the ends of the coils remote from the diaphragm. The reluctance of the path may be adjusted by an air gap placed therein or by other suitable means.

Two examples of my invention are shown 35 in the accompanying drawings.

Figs. 1 and 2 show parts of a telephone receiver, where A is the magnet whose polar extensions B carry the coils C in the usual way. Fig. 3 illustrates a modification of 40 the shunt path. In Fig. 1 the lower cheeks D of the coil are of iron or other suitable magnetic material and have their adjacent edges arranged with an air gap E of suitable length between them to provide the desired 45 magnetic reluctance.

Instead of or in addition to the cheeks D

iron pieces F as shown in Fig. 2 may be attached to the pole pieces B, with a definite air gap E¹ between them, or the said pieces F may be adjustably attached to enable the 50 air gap to be suitably adjusted.

Other means for obtaining the requisite degree of reluctance in the shunt path may be adopted without departing from the scope of the invention, as for instance, the pole 55 pieces may be joined by magnetic material of small enough cross section in any part to limit the flux to the desired extent.

As shown in Figure 3, the pole pieces B' have metal extensions G, the ends of which 60 are spaced apart and are connected together by a member H of reduced cross sectional diameter in order that there may be magnetic reluctance to the members introduced 65 in the pole pieces.

What I claim and desire to secure by Letters Patent is:—

1. A telephone receiver comprising a diaphragm, a pair of pole pieces, a magnet, said pole pieces having lower extremities attached to the magnet, a pair of coils supported on the pole pieces with their upper ends adjacent the diaphragm and iron cheeks one at the lower end of each coil, said iron cheeks forming an air gap and magnetic 75 shunt between their adjacent edges.

2. A telephone receiver comprising a diaphragm, a magnet, pole pieces having lower extremities attached to the magnet coils with their upper ends adjacent the diaphragm 80 supported on the pole pieces, and iron pieces connected to the pole pieces below the lower ends of the coils, said iron pieces forming an air gap and magnetic shunt between their adjacent edges.

In witness whereof I have hereunto set my hand in presence of two witnesses,

MERRITT SCOTT CONNER.

Witnesses:

ROBERT BERESFORD WEAVER,
RICHARD EDMUND ROBINSON.
